(57) **CLAIM**

We claim the ornamental design for replaceable dockable membrane module, as shown.

DESCRIPTION

FIG. 1 is an upper front perspective view of a replaceable dockable membrane module.

FIG. 2 is a lower front perspective view of the replaceable dockable membrane module depicted in FIG. 1.

FIG. 3 is a front elevation view of the replaceable dockable membrane module depicted in FIG. 1.

FIG. 4 is a rear elevation view of the replaceable dockable membrane module depicted in FIG. 1.

FIG. 5 is a right side elevation view of the replaceable dockable membrane module depicted in FIG. 1.

FIG. 6 is a left side elevation view of the replaceable dockable membrane module depicted in FIG. 1.

FIG. 7 is a top plan view of the replaceable dockable membrane module depicted in FIG. 1; and,

FIG. 8 is a bottom plan view of the replaceable dockable membrane module depicted in FIG. 1.
